DESIGN FOR A CAPE.

Design No. **6,641**, dated May 6, 1873

UNITED STATES PATENT OFFICE.

MARTIN LANDENBERGER, JR., OF PHILADELPHIA, PENNSYLVANIA.

DESIGN FOR A CAPE.

Specification forming part of Design No. 6,641, dated May 6, 1873; application filed April 8, 1873.

To all whom it may concern:

Be it known that I, MARTIN LANDENBERGER, Jr., of Philadelphia, Pennsylvania, have invented a Design for a Garment, of which the following is a specification:

The figure in the accompanying drawing clearly represents my design for a garment.

The latter in some respects resembles the garment known as a circular, it being provided with a hood, A, and being rounded at its lower edge a. This lower edge, however, merges into wings b b, which give the garment the peculiar appearance represented. The garment is, in the present instance, slashed or split at c, but this is immaterial and may be omitted, and both the hood A and body of the garment are ornamented by a deep fringe,

d, the hood being further ornamented by a bow, e, and an interior row of buttons and narrow fringe.

Irrespective of colors employed, I claim—

1. The design for the garment having the outline substantially as shown and described.
2. The design for the whole garment with its minor ornamentation, substantially as described, and as represented in and by the accompanying drawing.

In testimony whereof I have signed my name to this specification in the presence of two subscribing witnesses.

MARTIN LANDENBERGER, JR.

Witnesses:

J. J. BUCHEY,
JNO. JAY WARD.
